ATTORNEY

UNITED STATES PATENT OFFICE

WILLI LOHMAN, OF NEW YORK, N. Y.

TOILET STAND

Application filed October 10, 1929, Serial No. 398,799. Renewed December 12, 1931.

This invention relates to toilet stands and in particular to a stand adapted to individually support and protect tooth-brushes and to maintain one or more tooth-brushes in a sanitary and easily accessible condition but preventing accidental contact with foreign bodies.

An object of the present invention is to provide a stand having individual retaining means for tooth-brushes which will enclose the tooth-brushes in a sanitary protector and which will permit a current of water or other fluid to be passed over the brushes and drained therefrom.

Another object of the invention is to provide a hood adapted to surround portions of a tooth-brush to prevent it from coming in contact with foreign objects and which will permit the brush to be readily removed and replaced in position.

Another object of the invention is to provide a stand having a support for one or more brushes and other toilet articles, and an enclosure surrounding the upper portion of a tooth-brush through which water or other fluid may be caused to flow over the brush and to drain from the brush and from the support.

A still further object of the invention is to provide individual funnel members resting upon the support and disposed directly below the enclosure within which a tooth-brush may be positioned, so that when a fluid is admitted to the enclosure it will drain through the funnel member.

With these and other objects in view my invention includes the following features of construction and operation which will be more clearly understood as the specification proceeds.

In the drawing annexed hereto and forming a part of this specification, I have shown several embodiments of the invention which are now deemed preferable, but it will be understood that the invention can be otherwise embodied without departing from the spirit of the invention, the claims appended hereto more clearly defining and limiting the invention.

In the drawing—

Fig. 1 is a complete view in elevation of a

toilet floor stand made in accordance with the present invention;

Fig. 2 is a fragmentary view of the stand shown in Fig. 1 taken from the right hand side of Fig. 1;

Fig. 3 is a plan view of the upper portion of the stand;

Fig. 4 is a plan view of a table form of stand.

Referring more in detail to the figures of the drawing, and first to Figs. 1, 2 and 3, I provide a stand having a column 10 on which is mounted one or more supports 11, the lower ones being used for miscellaneous toilet articles, and the upper platform or support 11 being used for supporting as shown at 12 tooth-brushes. Some or all of these platforms or supports 11 may be provided with depressions 13 connected by conduits 14 to a pipe 15 extending vertically through the column 10 so that water or other fluid may drain from the platforms 11 into the conduits 14 and pipe 15 within the column 10 from which it may be withdrawn by any appropriate means not shown.

The upper portion of the column 10 is provided with branches 16, one being provided for each tooth-brush holder and as many being utilized as may be found convenient or desirable. Each of these branches 16 is provided with a hood portion 17 preferably mounted flexibly relative to the branch 16 of the column 10 so that it may be tilted in any direction, but which is adapted to remain normally in horizontal position. This hood portion 17 has a depending or apron portion 18 directly attached thereto which may be made of glass, celluloid or other material. Surrounding the lower portion of the apron portion 18 and tapering inwardly to the depression 13 within the platform or support 11 is a funnel shape enclosure 19 completely enclosing the tooth-brush 12 and preventing it from coming in accidental contact with foreign objects. The lower end of the funnel member 19 merely rests within the depression 13 so that by lifting it slightly it may be removed and the tooth-brush 12 taken from the apron member 18.

Water or other fluid may pass through the

branch 16 from a supply pipe 20 within the column and through the hood member 17 so that it will fall upon the tooth-brush 12 thus completely cleansing it in a perfect manner and preventing it from thereafter coming in contact with foreign objects. This fluid will be withdrawn from the lower end of the funnel member 19 through the passages and conduits 14 and 15 in the support 11 and column 10. A valve 21 positioned at the upper end of the column 10 and previous to the point of separation of the branches 16 therefrom permits the fluid supply to be controlled as desired.

15 On the support 11 may also be provided special recesses or accommodations for toilet articles such as shown at 22.

20 In Fig. 4 is shown a modification of the invention adapted to be mounted on a table or other support above the floor. In this form of the invention the support or platform 23 forms the base of the stand from which the column 24 is supported. This column 24 may be similar to that shown in Fig. 1 except that the water connection may be omitted. As the remaining parts of this form of stand are similar in every way to those previously described in connection with Fig. 1 further description is not thought to be necessary.

30 I claim:

- 35 1. A toilet stand comprising in combination, a support for a tooth-brush, a hood for enclosing the upper end of the tooth-brush, and a funnel member resting on said support and enclosing the lower portion of said hood, whereby said tooth-brush will be completely enclosed and easily removed upon removal of the funnel member.
- 40 2. A toilet stand comprising in combination, a column, a support, a plurality of branches to said column above said support, fluid supply conduits through said column and branches, a valve controlling the supply of fluid to said branches, a hood member on each of said branches communicating with the conduit therein and adapted to individually cover and partially enclose a tooth-brush, and means to drain fluid supplied to said hood members through said support and column.

WILLI LOHmann.
